EXTENSIBLE CURTAIN ROD DEVICE

John Di Martino, Brooklyn, N. Y.

Application December 26, 1942, Serial No. 470,232

6 Claims. (Cl. 211—105.3)

This invention relates to extensible curtain rod devices.

One object of the invention is to provide a device of the character described having improved means whereby an extensible curtain rod and its holders are adapted to be made of wood.

It will be appreciated that extensible curtain rod devices when made wholly and completely of wood in all features and details, create problems which did not exist in metal devices, particularly so if quantity production is considered and if the price range is to be kept at very low levels somewhat similar to those for the cheapest metal devices. Whereas metal can be easily stamped, bent, riveted, spot welded, and furnished with riveted or press fitted hooks, pins or spring portions, these features or characteristics are not available for wooden devices. The latter must be laboriously cut and fashioned, and considerable time is involved even if machinery is used, including millers, shapers, drill presses and grinders. The strength is much less than that of metal, especially along the grain. Hence there is the added problem of compactness in order not to render the article bulky and to conserve wood. With curtain rods it is also necessary that they shall be capable of insertion into the small hems of curtains which may have been mounted on metallic rods.

It is therefore an object of the invention to provide an improved curtain rod device which shall solve the difficulties above mentioned and afford a reenforced, strong, compact structure, which is durable, neat, reliable and efficient in use.

Other objects and advantages of the invention will become apparent as the specification proceeds.

With the aforesaid objects in view, the invention consists in the novel combination and arrangements of parts hereinafter described in their preferred embodiments, pointed out in the subjoined claims, and illustrated on the annexed drawing, wherein like parts are designated by the same reference characters throughout the several views.

Figure 1 is a fragmentary view in front elevation showing a curtain rod device embodying the invention.

Fig. 2 is a top plan view thereof.

Fig. 3 is a bottom edge of the curtain rod per se.

Fig. 4 is an enlarged view in side elevation of a holder for the curtain rod, according to the invention.

Fig. 5 is a sectional view thereof.

Fig. 6 is a top plan view thereof.

Fig. 7 is a sectional view of the curtain rod.

Fig. 8 is a side view of a modified curtain rod.

Fig. 9 is a sectional view thereof.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Referring in detail to the drawing, 10 denotes a curtain rod device embodying the invention. The same may include a curtain rod 11 which is 20 extensible, since it consists of a plurality of members 12, 13 having telescopic or dovetailed sliding engagement with each other. For example, the member 12 may be considered the female member, being provided with an undercut groove 14, while the member 13 may be considered the male element, being provided with a longitudinal dovetail portion or flange 15. The latter may fit in the groove 14 quite snugly, preferably with a fair degree of friction so as to prevent the members 12, 13 from accidentally sliding relatively to each other. This facilitates mounting of the curtain rod 11 in its holders, as herein-after described. Hence the curtain rod, carrying the curtains, will not ordinarily lose its 30 lengthwise adjustment or slip and complicate the mounting thereof.

Each of the members 12, 13 is provided with openings or notches at one edge, which, in the mounting position, becomes the lower edge.

40 Thus the member 12 has notches 12a and 12b, and the member 13 has notches 13a and 13b. The members 12, 13 may be the same in length, and all the notches are placed in identical relations to the ends of the members. As shown in

45 the drawing, the notches 12a and 13a are at the outermost ends of the curtain rod 11, in operative position, and the notches 12b and 13b are in inward inoperative position. But it is possible to reverse these positions and render the notches 12b, 13b operative by merely reversing the direction of relative sliding between the members, as will be readily apparent. Thus the curtain rod 11 is adapted for absolutely fool-proof use.

50 At 16 is shown a curtain rod holder embodying

the invention. The same may include a block having a back or flange part 17 formed with parallel holes 18 through which screws can be passed to secure the holder to a wall or window frame. Carried by the part 17 is a head 19 having one or more slots 20 which open upwardly to individually receive curtain rods such as shown at 11. By providing two slots, provision is made for hanging two curtains on separate curtain rods 11, as in the case of overlapping right and left curtains. The depth of the slots 20 is sufficient to receive the curtain rods, and the width thereof is preferably adapted for only one of the members 12, 13 of a curtain rod, as shown, in order to maintain strength and compactness of the holder 16. It is important to note that the slots 20 extend clear through from side to side of the holders so that the same are interchangeable and each may be used at the left or right.

It is essential to prevent the curtain rod from slipping endwise from the slots 20, either accidentally, or in course of adjusting the folds or pleats in the curtain, or by reason of a pull at a lower part of the curtain. A second consideration is that any locking engagement which may be used shall not require the use of metallic or moving parts, which may make the device prohibitive for the low price field. Supplemental to this is the utilitarian consideration that the curtain rod shall be positively locked by merely placing it in the slots 20. A third requirement is that any locking feature shall preferably reenforce the wood which is considerably weakened by the slots 20, and tends to break along the grain, which extends as in Fig. 5. It may be noted that if the grain extended horizontally the parts perforated by the holes 18 would be too weak, and might be split by the heads of the attaching screws, and the vertical portions 21, 22 would be liable to breakage.

All of the foregoing considerations are met by drilling a hole and inserting therein a pin 23 which is glued or cemented in place preferably throughout its length. This pin 23 may extend from front to back of the holder, but desirably the front is left intact for appearance. Thus the pin, which may be quite thick, amply reenforces the head 19 near the base of the slots 20 and resists bending and tension stresses which would crack the wood. The lower part of the head 19 requires no such reenforcement since any downward pull causes compression strains on its fibers.

Within the slots 20, the pin 23 presents locking pin portions which may be flush with the bottoms of the slots or above the same, and which are central to the length of the slots. These portions 24 are adapted to be readily received in the notches 12a, 13a, or 12b, 13b, as the case may be, depending on which notches are in operative position. In this manner a plurality of curtain rods 11 may be mounted and locked on a pair of holders 16.

It is thus seen that the locking devices afforded meet all the requirements herein. They constitute more than mere projections, which might be prohibitive in cost, and which might fail to reinforce the holders, thus requiring the use of more wood, and rendering the holders bulky and expensive. It will be noted that the invention is also advantageous for use of curtain rods of fixed length.

The manner of using the device 10 will now be described. The operator inserts the curtain rod 11 into the hem of a curtain. She then places one

end of the curtain rod in a slot 20 of one holder whereupon a notch such as 12a seats around a pin 23. Accordingly this end of the curtain rod is locked, so that the latter may be inserted into a corresponding slot 20 of the companion holder and then adjusted in length for a similar locking engagement with a pin 23. Since this adjustment can be effected while the curtain rod rests in the slots 20, manipulation is greatly facilitated. The weight of the curtain and of the curtain rod help maintain the engagement which will not be disturbed by shifting the curtain, or arranging the folds or pleats thereof, or exerting an angular pull on the curtain.

In Figs. 8 and 9 is shown a modified extensible curtain rod 25 which is like that at 11, and includes members 26, 27. The female member 26 may be identical with that at 12, but the male member 27 differs from that at 13 merely in that a special dovetail 15 is omitted, because it requires considerable labor to manufacture. To the contrary, the member 27 may be made by merely beveling the longitudinal edges 28, so that the entire member 27 forms a dovetail, but without any undercuts. This smaller member 27 is reinforced by the member 26. In all other respects the members may be like those at 12, 13 and they are operative in the same manner as with notches 26a, 26b, 27a and 27b.

It will thus be seen that the devices fulfill the objects of the invention and are well adapted for practical use.

I claim:

1. A curtain rod device including a holder consisting of natural wood, comprising a block having a mounting flange-like portion and a head carried thereby and integral therewith, said head having an upwardly opening slot of substantial depth so as to be adapted to receive a curtain rod, a wooden pin extending through the head and passing through the lower part of the slot, said pin being glued in the head and reenforcing the head against breakage along the grain at the slot, and a curtain rod resting in the slot and having a notch to receive the pin to prevent the curtain rod from slipping out of the slot.

2. A curtain rod device including a holder consisting of natural wood, comprising a head having an upwardly open slot extending from side to side of the head, the grain of the wood being generally vertical, a pin extending through the head and passing through the slot at the lower portion thereof and being fixed to the head so as to reinforce the same from breaking along the grain, and a curtain rod resting in the slot and having a notch in its lower edge for receiving the portion of the pin exposed in the slot.

3. A curtain rod device including a holder having a head provided with an upwardly open slot extending transversely from side to side of the head, a pin in the head passing transversely through the slot at the lower portion thereof, and a curtain rod fitted in the slot and having a notch removably engaged with the pin.

4. A curtain rod device including a holder having a head having an upwardly open slot, a pin fixed in the holder and passing transversely through the lower portion of the slot, and an extensible curtain rod including slidingly engaging members, said members being adapted to be individually fitted in the slot, each of said members having notches in its lower edge adjacent to its ends, the notches being interchangeably engageable with the pin in the slot upon mounting the curtain rod upon a pair of said holders.

5. A curtain rod device including a holder having a head consisting of a fibrous material, the head having a plurality of transverse slots extending from side to side of the head, and a pin extending longitudinally through the head and thus passing transversely through the slots at the lower portions thereof, whereby the pin reinforces the head against breakage at the slots and permits a minimum of material to be used at the walls of the slots, and a curtain rod resting in the slot and having a notch for releasable locking engagement with the pin so that the cur-

tain rod can be removed without disturbing the pin.

5 6. A curtain rod device including a holder having a head consisting of natural wood and having an upwardly opening slot extending transversely from side to side of the head, a pin extending through the head including the slot transversely of the latter and being fixed to the head to reinforce the same against breakage at the slot, 10 whereby a curtain rod having a notch can be seated in the slot in locking engagement with the pin.
